(57) **CLAIM**

The ornamental design of a keyboard image for a touch screen, as shown and described.

DESCRIPTION

FIG. 1 is a front view of a keyboard image for a touch screen showing our new design; and,

FIG. 2 is a second embodiment thereof.

The broken line showing of a touch screen in both views forms no part of the claimed design.

1 Claim, 2 Drawing Sheets

FIG. 1

FIG. 2
